ZEBINA EASTMAN, OF CHICAGO, ILLINOIS.

Letters Patent No. 68,421, dated September 3, 1867.

IMPROVEMENT IN RAILWAYS.

The Schedule referred to in these Letters Patent and making part of the same.

TO ALL WHOM IT MAY CONCERN:

Be it known that I, ZEBINA EASTMAN, of Chicago, in the county of Cook, and State of Illinois, have invented a new and useful Improvement in Railways for Cars and Vehicles; and I do hereby declare the following to be a full, clear, and exact description of the nature, construction, and operation of the same, reference being had to the accompanying drawings, which are made part of this specification, and in which—

Figure 1 is a plan of a railway illustrating my improvement.

Figure 2 is a vertical transverse section of the railway with the wheels running thereon; and

Figure 3 is a view similar to fig. 2, with a modification.

Similar letters of reference indicate corresponding parts in the several figures.

In carrying out my invention, I construct rails for street and other roads or ways of a concave, grooved, or cup form, and form the same with a rib or flange on their under sides to strengthen the rails and also to insert and hold them tightly in position. When the rails are laid their top surfaces lie flush or even with the ground, paving, or way on or in which they are laid. The wheels of the street or other cars which are to run upon such rails are formed with convex rims, or, in other words, the rims of the wheels have a configuration negative to that of the surface of the rails in or upon which they run. The rim of the wheel is somewhat smaller or narrower than the grooves or concavities of the rails in order that the bearing point of the wheel shall be confined to a small surface so as to avoid friction and enable the wheels to travel with freedom. The upper surface of the rail at each side of the groove is notched or suitably roughened to prevent the horses from slipping.

In order that others skilled in the art to which my invention appertains may be enabled to fully understand and use the same, I will proceed to describe it in detail.

In the accompanying drawings, *a a* may represent a pair of rails or trams which are formed with concavities in their upper surfaces, as shown in fig. 2. *b* is the rib formed on the under side of the rail or tram and inserted into the grooves of the bearings *c'*, which are formed on the ends of the ties *c*, which may be bolted to wooden sleepers or otherwise secured. *d d*, fig. 2, represent the wheels with convex rims somewhat narrower than the grooves of the rails *a a*, so that the wheels shall have but a small frictional surface, and at the same time be allowed a degree of lateral play in order to adapt the car or vehicle to run easily and prevent binding or running off the track in turning curves. By referring to the drawings it will be seen that the highest points of the rails *a a* are flush or even with the surface of the roadway, paving, or thoroughfare upon which the railway or tram is to be laid. Hence the wheels of cars or vehicles may be readily run upon or off of the rails, while the latter do not constitute any obstruction to the passage across them of the wheels of wagons and carriages. In cities the rails thus formed and laid form a common railway or tram upon or in which cars, carriages, wagons, and vehicles of every description may run with equal facility, inasmuch as the rails *a* are especially adapted for the reception of the wheels of ordinary vehicles, whose rims are invariably made with a greater or less degree of convexity. The upper surface of each rail *a*, at either side of the concavity therein, is formed with square notches *a'* about one-half of an inch broad, about the same distance apart, and about one-quarter of an inch in depth. This notching is designed to form a rough surface for the horses' shoes in order to prevent slipping when the horses tread upon the rails. As a rule I use rails or trams with a concave surface on both sides of the road or way, but sometimes, however, I employ the tram or rail with a concave surface on one side of the track only, and on the other side I lay or secure in the ground a flat rail, consisting of a plate or piece of iron somewhat broader than the concave rail, as shown in section in fig. 3. By this means cars or carriages of different widths are enabled to run freely and easily on the tram with the wheels on one side in the grooved rail and the wheels on the other side on the flat rail.

Having thus described my invention, what I claim as new herein, and desire to secure by Letters Patent, is—

The rail *a*, having a longitudinal groove or concavity in its upper surface adapted for the reception of the convex rims of wheels of cars and other vehicles, and formed with a downwardly projecting rim, *b*, for securing the rail in position upon the ties, when the upper edge of the rail on each side of the groove is notched in the manner and for the purpose described.
